No. 36,782.

Patented February 9, 1904.

UNITED STATES PATENT OFFICE.

CHARLES W. ROBINSON, OF SAN DIEGO, CALIFORNIA.

DESIGN FOR A DINNER-PLATE OR SIMILAR ARTICLE.

SPECIFICATION forming part of Design No. 36,782, dated February 9, 1904.

Application filed January 7, 1904. Serial No. 188,149. Term of patent 7 years.

To all whom it may concern:

Be it known that I, CHARLES W. ROBINSON, a citizen of the United States, residing at San Diego, in the county of San Diego and State of California, have invented a new, original, and ornamental Design for Dinner-Plates and Similar Articles, of which the following is a specification, reference being had to the accompanying drawing, forming a part hereof.

In the figure of the drawing a dinner-plate is shown illustrating my new design.

I claim—

The ornamental design for a plate or similar article, as shown.

C. W. ROBINSON.
